UNITED STATES PATENT OFFICE

165,848

FOOD MIXER OR THE LIKE

Ivar Jepson, Oak Park, Ill., assignor to Sunbeam Corporation, Chicago, Ill., a corporation of Illinois

Application January 16, 1951, Serial No. 13,824

Term of patent 14 years

(Cl. D44—1)

To all whom it may concern:

Be it known that I, Ivar Jepson, a citizen of the United States, residing at Oak Park, in the county of Cook, and State of Illinois have invented a new, original, and ornamental Design for a Food Mixer or the like, of which the following is a specification, reference being had to the accompanying drawings, forming part thereof.

In the drawings:

Fig. 1 is a perspective view of a food mixer or the like embodying my new design;

Fig. 2 is a side elevational view; and

Figs. 3 and 4 are front and rear elevational views respectively.

The dominant features of the design reside in the portions shown in full lines.

The ornamental design for a food mixer or the like, substantially as shown and described.

IVAR JEPSON.
